UNITED STATES PATENT OFFICE

JERIE EVICH, OF SANTA BARBARA, CALIFORNIA

ATTACHMENT FOR HAMMERS

Application filed May 22, 1930. Serial No. 454,807.

My invention relates to machinists' hammers and especially to those known as lead hammers. It particularly seeks to provide an attachment by which a machinist's ordinary hard head hammer may be rendered fit for use as a soft head hammer whereby the same may be employed in hammering or tapping shafts or pipes having threads.

More particularly the invention has for its object to provide an attachment which may be removably held in place on a striking end of the hammer head and which comprises a collar in which is mounted the soft metal striking element or plug, the collar being so held on the hammer head that it may be removed and replaced at will.

Other objects will in part be obvious and in part be pointed out hereinafter.

To the attainment of the aforesaid objects and ends the invention still further resides in the novel details of construction, combination and arrangement of parts, all of which will be first fully described in the following detailed description, then be particularly pointed out in the appended claims, reference being had to the accompanying drawing, in which:—

Figure 1 is a perspective view of a hammer with my invention applied.

Figure 2 is a side elevation of the hammer head with the invention in place, the collar being shown in vertical longitudinal section and the plug being in part broken away.

Figure 3 is a horizontal section on the line 3—3 of Figure 2.

Figure 4 is a similar section of a modification.

In the drawing, in which like numerals of reference indicate like parts in all of the figures, 1 represents the hard head of a machinist's hammer, 2 the handle, and 3 the cylindrical flat faced striking end of the hammer head. It is on this end 3 that the attachment constituting my invention is designed to be placed.

The attachment comprises a collar 4 which may be cut from a section of pipe, the collar having a pin hole 5 through which a cotter pin 6 may be inserted. Within the collar 4 is located the plug 9 of soft metal such as

lead, brass or suitable alloy, the plug being held in place by the cotter pin 6. When made of lead the plug may be poured into the collar while the lead is in the molten state, and the pin 6 have its end imbedded in the molten lead. When, however the plug 9 is to be made of brass or other alloy it may be provided with grooves 10 and a splitting edge 11 whereby when the cotter pin 6 is forced in through the hole 5 its tangs will be spread 60 into the grooves 10 and thus lock the plug and the pin in position against accidental separation.

Of course, when it is desired to remove the plug 9 from the collar 4 this can be done by simply withdrawing the cotter pin 6 and driving the plug out.

In practice, the collar 4 fits over the end 3 of the hammer with the plug 9 in contact with the striking face of the hammer end, in which position it is held against accidental dropping off by means of a coil spring 7 that is looped around the handle 2 and has its ends 8 hooked into the eye of the cotter pin 6. Of course, any other suitable elastic member 7 may be employed for the purpose.

When it is desired to use the hammer for tapping threads all that is necessary is to place the collar 4 with its plug 9 over the end 3 of the hammer, loop the spring 7 around the hammer and connect its ends to the cotter pin 6. When it is desired again to use the hammer in the ordinary way it is a simple matter to remove the attachment by simply unhooking the spring 7 and slipping off the collar.

From the foregoing description, taken in connection with the accompanying drawing, it is thought the construction, operation and advantages of the invention will be clear to those skilled in the art to which it relates.

My invention, as will have been seen, is really an improvement for machinist hammers such as mechanics use, and I call it a quick attachable soft metal hammer face. The combination of metal-material used in my invention can be made up by using solid lead or copper or brass alloy or babbitt, or by mixing some of these metals together to

produce a wearing material for mechanical use as a soft metal hammer.

What I claim is:

1. In combination with a hammer having a head with an elongated striking end, of a collar fitted over said end, a metal striking plug in said collar, a cotter pin passing through an aperture in said collar with its tangs imbedded in said plug, and a coil spring looped around said handle with its ends secured to said cotter pin.
- 5 2. The combination of a hammer having a head with an elongated striking end, with a collar fitted over said end, a soft metal striking plug in said collar, means securing said plug to said collar, and yieldable means connecting said handle and said collar to hold said collar on said hammer end.
- 10 3. The combination of a hammer having a head with an elongated striking end, with a collar fitted over said end, a soft metal striking plug projected into the collar, and means passing through the side wall of the collar into the side of the plug within the
